UNITED STATES PATENT OFFICE.

CANARD J. WALTERS, OF ELLAMAR, TERRITORY OF ALASKA.

TURBINE-ENGINE.

1,353,687.

Specification of Letters Patent. Patented Sept. 21, 1920.

Application filed July 31, 1917. Serial No. 183,784.

To all whom it may concern:

Be it known that I, CANARD J. WALTERS, a citizen of the United States, residing at Ellamar, Territory of Alaska, have invented new and useful Improvements in Turbine-Engines, of which the following is a specification.

This invention relates to a turbine, and it has for its primary object to provide a structure capable of receiving its energy from the expansive action of ignited gases.

An object of the invention is to provide simple means for putting a fluid under pressure upon explosion of a gas and controlling the flow of this fluid to either of a plurality of units through the action of a single operation of a lever.

Besides the above my invention is distinguished in the novel manner of utilizing all the expansive action of the fluid by constructing a turbine so that the fluid will act successively upon a plurality of sets of blades carried by a rotor.

With these and other objects in view the invention will be better understood from the following detailed description taken in connection with the accompanying drawings, wherein—

Figure 1 is a diagrammatic view of my invention.

Fig. 2 is an enlarged side elevation of two propelling units.

Fig. 3 is a cross sectional view through one of the units.

Fig. 4 is a longitudinal sectional view through one of the units.

Fig. 5 is a side elevation of the rotor.

Fig. 6 is an interior view of a portion of the stator.

Figs. 7 and 8 are detail views illustrating the valve mechanism and associated parts for feeding fuel to the expansion cylinder.

Fig. 9 is a fragmentary sectional view of the fuel pump.

Referring to the drawings, the engine may be said to comprise two units 1 and 2, as shown in Figs. 1 and 2, one unit being employed for driving the engine shaft in one direction, and the other unit being used for driving the engine shaft in the opposite direction. Referring primarily to Figs. 3, 4 and 5, it will be observed that each unit comprises a rotor casing 3 of a generally cylindrical formation comprising oppositely located heads 4 and having in the peripheral wall thereof arcuate channels 5 for the

movement of the expansive fluid admitted to the rotor casing 3. The formation of one of said passages 5 is best illustrated in Fig. 3 wherein it will be seen that it extends throughout a greater portion of the circumference of the casing 3, intersecting an intake port 6 to which leads a fluid feed pipe 7. There is no direct communication between passages 5, but the fluid having acted upon a rotor exhausts through a passage 8 into the next passage 5 in the series.

The rotor is composed of a plurality of cylindrical sections 9 arranged side by side as shown in Fig. 5, said sections being the duplicate of each other in all respects and each section being formed in the periphery thereof with an annular series of depressions 10 forming pockets or buckets and shoulders within and against which the fluid under pressure acts to impart rotary motion to the entire rotor of each unit according to the direction in which the engine is being driven. The rotor sections are arranged in a slightly spaced relation to each other as shown in Fig. 5 so as to admit of the use of intervening division pieces or partitions 11, shown in Fig. 4. These partitions divide the interior of the stator or casing 3 into a plurality of compartments, in each of which one of the rotor sections 9 operates. As shown in Fig. 4, the expanding fluid entering through the inlet port 6, flows around the initial arcuate passage 5 and then as indicated in dotted lines in Fig. 3 flows through the exhaust or transfer passage 8 into the arcuate passage 5 of the next adjacent section of the rotor, this continuing until the fluid, when it is almost completely expanded, passes through an exhaust pipe 12 controlled by a valve 13 to the atmosphere. Each inlet pipe 7 is controlled by an inlet valve 14. The general arrangement of the valves 13 and 14 is illustrated in Fig. 2 wherein it will be observed that the arms 15 of all of said valves are operatively connected to a common operating rod 16 which is in turn connected to and controlled by a single manually operable lever 17 pivotally supported on a bracket 105 and equipped with a thumb latch 18 which engages an arcuate rack 19. By manipulating the lever 17, the inlet and exhaust valves may be opened to any desired degree or entirely closed. By swinging the lever 17 to the full extent of its movement in either direction, the inlet and exhaust valves of

one of the engine units 1 and 2 may be thrown out of operation and the other unit thrown into operation for changing the direction of rotation of the engine shaft 20 5 upon which the rotors are fastened by any suitable means.

As shown in Fig. 4 each of the rotor casings is furnished with stuffing boxes 21 at the opposite ends thereof and also provided 10 with lubrication holes 22 leading to those portions of the rotor shaft which are journaled in the casings or stators 3. As shown in Fig. 3, each arcuate passage 5 is intersected by an arcuate series of velocity increasing passages 23 and the discharge ends 15 of the passages 23 intersect a corresponding number of expansion chambers or pockets 24 formed in the inner face of the stator. The last one of these expansion chambers 20 24 communicates directly with the receiving end of the transfer passage 8. Fig. 3 also illustrates the formation of the entire rotor casing or stator into two semi-circular sections which are flanged as shown at 25 and 25 secured together by fastening means 26 such 28 as bolts which may be also passed through suitable engine bearers or supports 27 of any 30 suitable formation. Figs. 1 and 2 show at 35 the laterally deflected or inclined portions of the casing containing the passages 5 and the transfer passages 8 and indicate how the expanding fluid after acting upon one section of the rotor is transferred to the adjacent section, this operation being continued until all of the rotor sections have 40 been acted upon by the expanding fluid, whereupon the latter is released through the adjacent exhaust pipe 12.

29 designates an internal combustion cylinder having adjacent to one end thereof a laterally offset receiving chamber. 31 designates a compressed air tank which may have air compressed therein by any suitable air compressor or pump, the tank 31 being 45 equipped with a pressure gage 32. From the tank 31 a compressed air pipe 33 leads directly to the receiving chamber 30 of the cylinder 29, said pipe 33 being controlled by a regulating valve 34. 35 represents a fuel 50 tank which may be arranged at an elevation above the engine to provide for a gravity feed. 36 designates a fuel feed pipe leading from the tank 35 to the compressed air pipe 33 at the point 37 between the valve 55 34 and the receiving chamber 30 of the cylinder 29. The pipe 36 is controlled by a regulating valve 38 and in connection with the feed pipe 36, I employ a force feed pump 39. I also pass a portion of the fuel feed 60 pipe 36 through a part of the cylinder 29 as indicated by dotted lines in Fig. 8 so that the hydro-carbon or other fuel oil may be heated preparatory to being taken up by the compressed air in the pipe 33. 40 designates a spark plug arranged in any suit- 65

able ignition circuit for firing the charges in the cylinder 29. The fuel feed pipe 36 may be equipped with an additional and more conveniently located regulating valve 41 if so desired, the latter being shown adjacent to the cylinder 29.

The mixture ignited in the cylinder 29 is carried through a pipe 42 controlled by a back pressure check valve 43 into a pressure tank 44 equipped with a pressure gage 45. From the tank 44, the fluid passes through either of the intake pipes 7 to the rotor casings or units 1 and 2. Each of the pipes 7 is preferably equipped with a cut off valve 46 in addition to the valves 14 hereinabove referred to.

47 designated an air compressor for forcing air into the tank 31. The compressor is illustrated in Fig. 1 as embodying two cylinders, the reciprocating pistons 48 of 85 which are connected by rods 49 to the wrist pins 50 of a pair of crank disks 51 mounted on a shaft journal in a bearing bracket 52 on the frame of the engine and operatively connected by gears 53 and 54 with the engine shaft. Compressed air pipes 55 lead from the cylinders 47 to the tank 31, back flow being prevented by check valves 56.

In order to provide for easy and reliable starting of the engine, each of the units 1 95 and 2 is equipped with a pressure manifold 57 with which one of the pipes 7 communicates at one end as shown in Fig. 1. The manifold 57 extends transversely of the several arcuate passages 5 and communicates 100 with each of said passages through a port 58 each controlled by a separate and independent valve 59. By opening the valves 59, full pressure may be delivered to each 105 rotor section. Likewise a lubricating manifold 60 may be used in conjunction with all of the rotor sections to simultaneously lubricate the meeting faces between said sections and the dividing partitions 11. The oil in each manifold 60 may be heated by a 110 portion of the hot gases in the adjacent manifold 57 by a small tubular connection 61 as shown in Fig. 1. The lubrication of the several rotor sections may be controlled by independently regulating valves 62.

The admission of explosive mixture to the receiving chamber 30 of the cylinder 29 is controlled by an inlet valve 63, see Fig. 7, said valve being mounted upon a valve stem 64 controlled by a tappet 65 which cooperates with a tappet bar 66 actuated by a cam 67 shown as having diametrically offset cam faces 68 and mounted upon a rotary shaft 69 which may be geared to and driven by the engine shaft 20 in any suitable way. 125 The valve 63 is held normally seated by means of a compression spring 70.

The pump 39 above referred to comprises in connection with a cylinder, a reciprocating pump piston 71 having attached there-

to a rod 72 carrying an eccentric strap 73 which encircles an eccentric 74 on the cam shaft 69 above referred to. The oil feed pipe 36 leads into the pump cylinder 39 and 5 contains a back pressure check valve 75. The other section of the feed pipe 36 leads off from the cylinder 39 and also contains a back pressure check valve 76.

From the foregoing description taken in 10 connection with the accompanying drawings, the operation of the engine will now be understood. As previously indicated, the engine comprises two power units 1 and 2, in which the rotor sections are reversely 15 disposed with relation to each other, adapting the engine to be reversed or driven in either direction. The supply of explosive fluid may be directed to either unit by the valve mechanism above described. The fluid continues to expand in connection with the 20 series of rotor sections of each unit until it is finally exhausted to the atmosphere. After passing around approximately three-fourths of the circumference of one rotor section, 25 the fluid is transferred to the adjacent section where a similar operation takes place, this being continued until the final exhaust port is reached. The manifold arrangement indicated at 57 in conjunction with the

valves 59, enables the full pressure to be 30 simultaneously delivered to each rotor section for starting purposes. After the engine starts, the valves 59 may be successively closed. After they are all closed, the expanding fluid will operate only on the initial 35 rotor section with its full force, and with decreasing force on each succeeding rotor section.

I claim:—

In a turbine engine, a rotor having a series of pockets in the periphery thereof, each pocket having a radial end wall and an inclined bottom wall, a stator having a series of pockets in its inner periphery, said second named pockets being similar to and 40 disposed reversely with respect to the first named pockets, an arcuate passage extending outside of said series of second named pockets, and a series of velocity increasing 45 passages having their receiving ends leading from said passage and their discharge ends leading through the radial end walls of said stator pockets, the stator being also formed with annular transfer passages establishing indirect communication through 50 the chamber to the succeeding passage.

In testimony whereof I affix my signature.
CANARD J. WALTERS.
